BOTTLE WRAPPING MACHINE

Application filed March 15, 1930. Serial No. 436,146.

My invention relates to improvements in bottle wrapping machines which are particularly adapted to apply to sealed bottles open ended paper wrappers which are normally flat when made and when opened conform substantially to the shape of the bottles to which they are applied. The objects of the invention are to pick up the collapsed wrappers, to open them and to apply them to the bottles as they are carried along upon a suitable conveyor.

The invention consists essentially of a bottle conveyor, wrapper chute, a suction device for progressively picking up a wrapper and delivering it to a further suction device which opens the wrapper and places it upon a bottle as said bottle is moved by the conveyor, as will be more fully described in the following specification and shown in the accompanying drawings, in which:—

Fig. 1 is a front elevational view of the invention.

Fig. 2 is a side elevational view of the invention.

Fig. 3 is a plan view of the invention.

Fig. 4 is a detail side view of the wrapper opening mechanism.

Fig. 5 is a front view of same.

Fig. 6 is a detail plan view taken on the line 6—6 of Figure 4.

Fig. 7 is a detail plan view of the bottle release mechanism to the wrapping mechanism.

Fig. 8 is a front view of same.

Fig. 9 is a detail view of the primary vacuum valve control.

Fig. 10 is a sectional view of the secondary vacuum valve control.

In the drawings like characters of reference indicate corresponding parts in each figure.

The numeral 1 indicates generally a frame consisting of uprights 2, tiers of transverse members 3, 4, 5, and 6, and longitudinal members 7. Journalled in suitable bearings upon the transverse members 5 is a longitudinally disposed drive shaft 8 having a pulley 9, and drive sprockets 10, 11 and 12, and at its front end a mitre gear 13 which latter drives a vertical shaft 14 through a mitre

gear 15. The sprocket 11 drives through a chain 16 a further sprocket 17 which is keyed to a longitudinal shaft 18 journalled in suitable bearings on the tier of transverse members 3. The shaft 18 is fitted at its rear end with a mitre gear 19 which in turn drives through a mitre gear 20 a transverse shaft 21 which is journalled in bearings 22 mounted upon the rear end of the longitudinal frame members 7.

At the front end of the machine a further transverse shaft 23 is journalled in bearings 24 and is fitted with a pulley 25 which is driven by a suitably supported conveyor belt 26 from a pulley 27 keyed upon the shaft 21.

The sprocket 10 drives a countershaft 28 through a chain 29 passing around a further sprocket 30, the countershaft being journalled longitudinally of the machine and having a crank 31 at its forward end which is connected to a slide 32 mounted upon a transverse counterweight rocking arm 33. The crank 31 is driven in a clockwise direction as viewed from the front, and in consequence the upstroke of the inner end of the rocking arm is accomplished at a greater speed than the downstroke. The inner end of the rocking arm is fitted with a universal joint 34 attached to the upper end of a connecting rod 35, the lower end of which connecting rod is fitted with a second universal joint 36 connected to a slide 37 to be hereinafter referred to in detail.

The sprocket 12 drives, through a chain 38 and a further sprocket 39, a hollow shaft 40 having at its forward end a hose coupling 41 and at its rear end a radial extension 42 which is outwardly branched as at 43 and fitted with a pair of suction cups 44. Fitted longitudinally of the upper run of the conveyor belt 26 are spaced guides 45 which serve to maintain the bottles carried therealong upon its longitudinal centre to align them with the capping mechanism. Mounted to one side of the machine is a wrapper chute or rack 46 having a front opening in which the wrappers are placed in inverted position and are urged towards the front opening which is provided with a suitable spring retainer 47 for the purpose of releas-

ably holding the foremost wrapper in position to be engaged by the suction cups 44 on the radial arm 42. Fitted adjacent the front end of the machine and about the conveyor belt 26 is a bottle release mechanism shown in Figures 7 and 8 and generally referred to by the numeral 48. A base plate 49 extends transversely of the machine between the upper and lower runs of the belt 26 and journaled through it is a pair of freely rotatable vertical shafts 50 fitted with intermeshing gears 51 of equal pitch diameter. These shafts are fitted with pairs of star wheels 52 having co-operating recesses 53 which are adapted when in register to permit the passage of bottles one by one therebetween, and when not in register to obstruct the movement of the bottles upon the belt. The rotation of the star wheels is effected indirectly from the moving belt 26 and a bottle carried thereon, the bottle being moved into opposing recesses 53 and into contact with the marginal edges thereof causes said wheels to turn that the bottle may pass therebetween. Mounted upon one of the shafts 50 is a disc 54 having as many regularly spaced indentations 55 in its periphery as there are recesses in each of the star wheels, into each of which the upper end of a balanced trigger 56 is adapted to enter progressively to stop the star wheels from rotating immediately following the release and to prevent the passage of the next bottle.

Fitted upon the lower end of the shaft 14 is a cam 57 having a projection 58, shown in dotted line in Figure 7, which engages the lower end of the trigger 56 at a predetermined point of its rotation to rock the trigger and permit a further bottle to pass the star wheels that each successive bottle may be so timed on the conveyor as to receive a wrapper on reaching the wrapping mechanism. The slide 37 of the wrapping mechanism is a U-shaped member 59 the legs of which are fitted with pairs of bearings 60 slidably mounted upon a pair of spaced inclined guides 61 and a pair of forwardly projecting lugs 62 each of which support an inwardly projecting shaft 63. Fitted in front and parallel to the guides 61 is a pair of cam plates 64 which are so spaced as to permit the passage of the conveyor belt 26 and the bottles thereon, these cam plates are each provided with a cam slot 65 divided into relatively straight portions indicated by the numerals 66, 67, 68, 69 and 70 the purpose of which will hereinafter appear. Slidably mounted on each of the shafts 63 is a block 71 having a circular arm 72 which projects through its adjacent cam slot and adjustably supports at its outer end a tubular bracket or swan neck 73 having at its upper extremity a suction cup 74. The lower ends of the swan necks are fitted with flexible hose 75 leading to a valve generally indicated by the numeral 76 (see

Figure 10). The valve 76 is of the rotary type consisting of a hollow body 77 having an outlet connection 78 at one end, a cover 79 at the other and an inlet connection 80 in its side wall. A hollow cylinder 81 open at one end is rotatably mounted in the valve body 77 which is fitted with a stem 82 projecting concentrically through the cover 79 and is connected by a suitable coupling 83 to the rear end of the countershaft 28.

The cylinder 81 is provided with a peripheral port 84 which is adapted to be in register with the inlet connection during the time that the arms 72 of the wrapping mechanism are downwardly traversing the portions 67, 68 and 69 of the cam slots 65 and to be out of register during the remainder of the traversing cycles. A vacuum line, not shown, extends from the outlet connection 78 to a suitable vacuum pump, not shown. Mounted upon the vertical shaft 14 is a disc 85 having two peripheral gaps 86 spaced approximately 180 degrees apart.

Mounted adjacent the shaft 14 is a valve 87 having an inlet opening 88 connected to a suitable suction pump, not shown, and an outlet opening 89 connected by suitable piping to the hose coupling 41 on the tubular shaft 40, the valve is provided with a suitable seat and closure 90 and a vertical stem 91 which is fitted above the valve with a yoke 92 supporting a non-rotatable collar 93 having a horizontally projecting dog 94 capable of passing through either of the gaps 86 in the disc 85. Suitably mounted above the valve 87 is a small solenoid 95 having an armature connected to a vertical rod 96, the lower end of which rod projects through the collar 93 and is fitted with a light compression spring 97 and a nut 98 which serves as an abutment 106 for the lower end of the spring.

The numeral 99, (see Figure 3) indicates a light spring opened switch, disposed to one side of the conveyor belt 26 between the bottle release 48 and the wrapping mechanism, which is adapted to be actuated by each bottle passing therewith to close an electrical circuit in which the solenoid 95 is in circuit, so as to energize said solenoid that its plunger may be raised and the dog 94 brought into resilient contact with the underside of the disc 85, which disc in rotating brings one of the gaps 86 into register with the dog that the latter may be forced upwards through the gap, and in so doing raising the valve stem 91 and opening the valve. The valve when open permits the pump to exert a vacuum pull on the suction cups 44 to draw the foremost wrapper in the chute 46 into holding contact therewith, so that the wrapper is drawn from the hopper and carried through a semi-circular path into an upright position adjacent and between the upper end of the cam plates 64. When the wrapper reaches the position above described the sliding mem-

ber 59 has moved part way down on its stroke until the arms 72 are in the portions 67 of the cam slots 65 and the opposed suction cups 74 are in contact with opposite sides of the 5 wrapper and between the cups 44, and the valve 76 is open to produce a suction on the cups 74 to support the wrapper. Prior to the cups 74 taking hold, the bottle which has passed the spring opened switch 99 has 10 permitted it to open the circuit, de-energizing the solenoid 95 and allowing the dog 94 to rest upon the top face of the disc 85 and when the cups 74 having taken hold on the wrapper, the second gap 86 is in register with 15 the dog 94, so that the latter drops therethrough and allows the valve 87 to close, thus breaking the suction on the cups 44 and releasing their hold on the wrapper. The suction on the cups 74 is applied to opposite sides 20 of the wrapper so that as the arms 72 pass through the diverging portions 68 of the cam slots, the wrapper is opened up to substantially cylindrical form and is lowered over the neck of the bottle and as they pass 25 down the parallel portions 69 the wrapper is carried down to fully envelop the bottle. The closing of the rotary valve 76 is timed to correspond with the entering of the arms 72 into the lower diverging portions 70 of the cam slots so that suction is disconnected and 30 the cups let go their hold upon the wrapper.

The downward movement of the cups 74 is accompanied, on account of the inclination of the guides 61, with a forward movement corresponding in speed to that of the belt 35 and the bottle being wrapped, so that the stability of the bottle upon the belt is undisturbed. The upward movement of the cups 74 takes place before that next succeeding bottle is brought into position thereunder. If a bottle shortage occurs and at the proper 40 interval there is no bottle to close the switch 99, the solenoid is not energized to open the valve 87 and in consequence no suction is effected at the cups 44 which then fail to pick up a wrapper for delivery to the wrapping mechanism.

What I claim as my invention is:

1. In a machine for covering bottles with 45 open ended wrappers, a conveyor belt along which bottles are adapted to be carried, a wrapper delivery mechanism including a pair of inclined guides, a member reciprocable along said guides, a pair of arms fitted with suction cups, carried by said member, means for placing a wrapper between said 50 cups, means for separating the cups to open the wrapper as the member is moved downwards along the guides whereby the wrapper is placed above a bottle upon the conveyor belt, and means for controlling a suction to support the wrapper in contact with the cups 55 on the downward stroke of the member.

2. In a bottle wrapping machine having a 60 wrapper delivery mechanism disposed above

a belt on which bottles are adapted to be conveyed to be wrapped, a spacing device disposed above the belt comprising a pair of freely rotatable overlapping star wheels having opposing recesses adapted to permit the 65 passage of a bottle therebetween and timing means to prevent the rotation of the star wheels until a predetermined belt movement has taken place.

3. In a machine for covering bottles with 70 open ended wrappers, a continuously moving conveyor for moving bottles progressively, a wrapper delivery mechanism above the belt comprising a rotary suction arm adapted to pick up a wrapper and invert it, a pair of opposed suction cups, means for bringing the suction cups into contact with opposite sides of the inverted wrapper, means for causing the rotary arm to release the wrapper as it is engaged by the suction cups, means for moving the cups apart to open the wrapper and simultaneously lower said wrapper onto a moving bottle upon the belt.

4. In a machine for covering bottles with 75 open ended wrappers, a continuously moving belt adapted to convey bottles to be covered, a wrapper delivery mechanism having an arm for picking up a wrapper and disposing it above the conveyor, and a pair of suction cups for receiving the wrapper from the arm, 80 opening it and placing it upon a bottle travelling upon the belt, and means operable in response to a bottle shortage upon the belt for preventing the arm from picking up a 85 wrapper.

Dated at Vancouver, B. C., this 3rd day of February, 1930.
